Ch. Harten

Attorney

UNITED STATES PATENT OFFICE.

CLARK W. COOPER, OF ORLANDO, FLORIDA.

BUILDING BLOCK.

Application filed February 16, 1925. Serial No. 9,571.

To all whom it may concern:

Be it known that I, CLARK W. COOPER, a citizen of the United States, residing at Orlando, in the county of Orange and State 5 of Florida, have invented certain new and useful Improvements in Building Blocks, of which the following is a specification.

This invention relates to building blocks, and more particularly to ventilated concrete 10 blocks.

An object of the invention is to provide a building block of this character having free circulation of air to prevent dampness in a wall constructed of the blocks.

15 A further object of the invention is to provide a block having horizontal and vertical air passages connected to each other at intervals in order that air may freely circulate through the wall.

20 In the accompanying drawings, I have shown one embodiment of the invention. In this showing:

Figure 1 is a perspective view of a corner of a wall in which the building block is employed,

25 Figure 2 is a horizontal sectional view substantially through the center of a row of blocks,

30 Figure 3 is a vertical sectional view substantially on line 3—3 of Figure 1, and,

Figure 4 is a perspective view of one of the blocks.

Referring to the drawings, the reference numeral 1 designates a block as a whole,

35 which is substantially rectangular in cross section. The block is provided with a pair of spaced horizontal air passages 2 arranged near its front and rear faces. These passages may be of any desired cross section.

40 In the drawings, I have shown the passages rectangular in vertical cross section and extending from a point near the top of the block to a point near the bottom. Substantially equidistant from each end of the block,

45 I provide a vertical, oval-shaped passage 3 which is arranged between the horizontal passages transversely of the block (see Figures 2 and 3). At each end of the block, and in alignment with the passage 3, I provide

50 a semi-oval shaped passage 4, so that when two of the blocks are assembled in building the passages in the ends of the two adjacent blocks register with each other and form an oval-shaped passage similar to the passage 3. The horizontal passages 2 and the vertical passages 3 and 4 are connected to

each other at suitable intervals to provide means for free circulation of air. As shown (see Figure 3), I provide transverse passages 5 in the blocks which extend from the 60 passages 2 to the central vertical passages 3. Likewise, at the ends of the blocks, I provide substantially semi-circular depressions or recesses 6 in the end walls between the 65 passages 2 and the passages 3 and when two of the blocks are assembled, these semi-circular recesses in the end register with each other to form a substantially circular passage.

The upper and lower faces of the blocks 70 are provided with a plurality of horizontal grooves 7 and when the blocks are employed in a wall construction, the mortar 8 is adapted to enter these grooves (see Figure 3) to provide a more rigid construction. 75

The advantages of this block will be apparent from the foregoing description. The greatest objection to the use of concrete in buildings is dampness. It has heretofore been proposed to provide passages through 80 the walls of a concrete building for circulation of air to overcome this objection. However, the constructions heretofore provided for this purpose do not permit free circulation of air. By providing the connecting or lateral passages 5 and 6 between the horizontal passages 2 and the vertical 85 passages 3 and 4, free circulation of air is provided and the objection of dampness is overcome. 90

It is to be understood that the form of my invention herewith shown and described is to be taken as a preferred example of the same, and that various changes in the shape, size, and arrangement of parts may be resorted to without departing from the spirit 95 of the invention or the scope of the subjoined claims.

I claim:

1. A building block having horizontal air 100 passages arranged adjacent its front and rear walls, a vertical passage arranged between said horizontal passages, and a lateral passage connecting said vertical passage to said horizontal passages. 105

2. A building block having horizontal air 110 passages arranged adjacent the front and rear walls thereof and substantially parallel thereto, a vertical passage arranged between said horizontal passages, and a lateral passage connecting said vertical passage to said horizontal passages.

3. A building block having horizontal air passages adjacent its front and rear walls, said passages being substantially rectangular in cross section, an oval-shaped vertical passage arranged between said horizontal passages, and a lateral passage connecting said vertical passage to said horizontal passages.
4. A building block having horizontal air passages adjacent its front and rear walls, 10 said passages being substantially rectangular in cross section, an oval-shaped vertical passage arranged between said horizontal

passages, a lateral passage connecting said vertical passage to said horizontal passages, the end walls of said block being provided with semi-oval recesses arranged in longitudinal alinement with the oval-shaped vertical passage between said horizontal passages, and being further provided with semi-circular lateral recesses connecting said first 15 mentioned recess to said horizontal passages.

In testimony whereof, I affix my signature.

CLARK W. COOPER.
